UNITED STATES PATENT OFFICE.

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A PLATE OR ANALOGOUS ARTICLE.

Application filed April 28, 1922. Serial No. 2,016. Term of patent 7 years.

To all whom it may concern:

Be it known that I, HAROLD E. Nock, a citizen of the United States, residing at Newburyport, in the county of Essex and State of Massachusetts, have invented a new, original, and ornamental Design for a Plate or Analogous Article, of which the following is a specification, reference being had to the accompanying drawing, forming a part thereof.

In the accompanying drawing the figure is a plan view of a plate showing my new design. In the figure of the drawing a section only of the border ornamentation is shown.

I claim:

The ornamental design for a plate or analogous article, substantially as shown.

HAROLD E. NOCK.
